UNITED STATES PATENT OFFICE.

EPPA H. RYON, OF WALTHAM, AND RICHARD E. WELSH, OF NEW BEDFORD, MASSACHUSETTS, ASSIGNEES TO CROMPTON & KNOWLES LOOM WORKS, A CORPORATION OF MASSACHUSETTS.

PICKER-STICK CHECK.

1,366,952.

Specification of Letters Patent.

Patented Feb. 1, 1921.

Application filed February 26, 1920. Serial No. 361,499.

To all whom it may concern:

Be it known that we, EPPA H. RYON and RICHARD E. WELSH, citizens of the United States, said RYON residing at Waltham, in the county of Middlesex and State of Massachusetts, said WELSH residing at New Bedford, county of Bristol, and State of Massachusetts, have invented a new and useful Picker-Stick Check, of which the following is a specification.

This invention relates to a device for checking the movement of a picker stick and for bringing a shuttle gradually to rest at a predetermined point.

It is the object of our invention to provide a device which shall apply a gradually increasing friction pressure to the picker stick as the shuttle is boxed, and which shall promptly release all friction when the picker stick is given its operative movement in the opposite direction.

With this general object in view an important feature of our invention relates to the provision of yieldable friction members in connection with means for forcing said members against the picker stick with increasing pressure as the stick is moved toward the end of the lay. In the preferred form of our invention, an adjustable cam device is employed to produce such increasing pressure.

Our invention further relates to certain arrangements and combinations of parts which will be hereinafter described and more particularly pointed out in the appended claims.

A preferred form of our invention is shown in the drawings in which—

Figure 1 is a plan view of our improved check;

Fig. 2 is a similar view, partly in section, and showing the parts in a different position;

Fig. 3 is an end elevation of our invention applied to a lay, and

Fig. 4 is a transverse sectional elevation taken along the line 4—4 in Fig. 1.

Referring to the drawings, we have shown a lay 10 and a portion of a picker stick 11, both of the usual form. A U-shaped frame or casting 12 is rigidly secured to the lay 10 by an upwardly extending projection or bracket 13. The two portions of the casting 12 extend toward the center of the loom

upon both sides of the picker stick 11. A 55 pair of friction members 14, preferably of wood, are longitudinally slideable in recesses in the inner face of the frame 12, as best shown in Fig. 4.

Studs 15 are mounted in lugs 16 at the 60 open end of the frame 12, and project into openings 17 in the ends of the friction members 14. Each stud is provided with a washer 18 and a spring 19 by which its friction member is moved yieldingly toward the 65 end of the lay.

Each member 14 has a deep slot 20 by which one end of said member is divided into two parts 14^a and 14^b. The parts 14^a are positioned to engage the picker stick 11 70 as it moves between them toward the end of the lay, and the parts 14^b are beveled at their outer ends to engage inwardly-facing cam surfaces on a cam block 21 longitudinally adjustable in the recesses of the frame 75 12. Suitable adjusting screws 22 and 23 are provided for adjusting and positioning the block 21. A lug 24 extends inward from the block and serves to separate the members 14^a and limit movement thereof. 80

Having described the construction of our improved picker stick check we will now describe the method of operation thereof:

The springs 19 normally move the members 14 to the right, as shown in the drawings, until the beveled portions 14^b engage the cam block 21 and the friction portions 14^a engage the lug 24. As the shuttle enters the box, the picker stick is moved to the right in frictional engagement with the portions 14^a. Such engagement not only forces the portions 14^a apart, thereby increasing the friction, but also forces the portions 14^b against the cam block 21 by which said portions are moved inward, still further increasing the pressure upon the stick 11. The shuttle is thus brought to rest by the increasing friction applied through the portions 14^a to the sides of the stick 11. 90 95

When the picker stick is given its operative or picking movement in the opposite direction, the members 14 move with the picker stick for a sufficient distance to separate the beveled portions 14^b from the cam block, thereby releasing the friction upon 100 the stick. This release occurs within the first fraction of an inch of travel of the stick, as indicated in dotted lines in Fig. 105

2, and the stick is thereafter free to pick the shuttle.

We have thus provided a check which applies increasing force during the boxing of the shuttle and which is released with great promptness as soon as the operative picking movement is begun. Many of the advantages of our invention may be obtained by the use of a single friction member but the use of two members is preferred.

Having thus described our invention it will be evident that changes and modifications can be made therein by those skilled in the art within the spirit and scope of our invention as set forth in the claims, and we do not wish to be otherwise limited to the details herein disclosed, but what we claim is:—

1. In a loom having a lay and a picker stick, a picker stick check comprising a frame fixed to the lay, a pair of friction members mounted to slide in said frame with a limited longitudinal movement when engaged by said picker stick, and a device effective to force said members against said stick as said members are moved toward the end of the lay by said picker stick.

2. In a loom having a lay and a picker stick, a picker stick check comprising a frame fixed to the lay, a pair of stick-engaging members mounted in said frame and held for longitudinal movement only at one end thereof, said members being beveled at the opposite end, and a cam device engaging the beveled ends of said members, thereby forcing the same against the picker stick and limiting longitudinal movement of said members.

3. In a loom having a lay and a picker stick, a picker stick check comprising a frame fixed to the lay, a friction member mounted for limited longitudinal movement

in said frame, and a cam device fixed relative to the lay and effective to increase the pressure of said member on said stick as 45 said member moves longitudinally in said frame toward said device.

4. In a loom having a lay and a picker stick, a picker stick check comprising a frame fixed to the lay, a block longitudinally adjustable in said frame and having opposite inwardly-disposed cam faces, and a pair of friction members longitudinally movable in said frame and engaging said cam faces when moved toward the end of 55 the lay by the picker stick.

5. In a loom having a lay and a picker stick, a picker stick check comprising a frame fixed to the lay, a block longitudinally adjustable in said frame and having 60 opposite inwardly-disposed cam faces, and a pair of friction members longitudinally movable in said frame and engaging said cam faces when moved toward the end of the lay, each of said members being formed 65 of a single piece of wood slotted longitudinally at the end adjacent said block to provide yielding frictional contact with said picker stick and positive cam engagement with said block.

6. In a loom having a lay and a picker stick, a picker stick check comprising a frame fixed to the lay, a block longitudinally adjustable in said frame and having opposite inwardly-disposed cam faces, a pair of 75 friction members longitudinally movable in said frame and engaging said cam faces when moved toward the end of the lay, and springs to move said members toward said block.

In testimony whereof we have hereunto affixed our signatures.

EPPA H. RYON.
RICHARD E. WELSH.
